UNITED STATES PATENT OFFICE.

LEVERETT E. RHODES, OF HARTFORD, CONNECTICUT.

VERTICAL-SHAPER ATTACHMENT.

Application filed September 19, 1921. Serial No. 501,602.

To all whom it may concern:

Be it known that LEVERETT E. RHODES, a citizen of the United States, residing at Hartford, in the county of Hartford and 5 State of Connecticut, has invented a new and useful Improvement in Vertical-Shaper Attachments, of which the following is a specification.

This invention relates to those metal cutting tools known as shapers. These machines are built with horizontally reciprocating rams for making horizontal cuts and with vertically reciprocating rams for making vertical cuts.

10 The object of this invention is to provide a simple and rigid attachment with a vertically reciprocating ram that may be easily and quickly substituted for the horizontally reciprocating ram and connected with the 20 standard operating mechanism for the purpose of transforming the horizontal shaper into a vertical shaper when it is desired to make vertical cuts instead of horizontal cuts.

This object is attained by providing a 25 housing with a saddle carrying a vertical tool holding ram and horizontal lever for reciprocating the ram, designed in such form that the housing may be set into and secured in the desired position in the ways at the top 30 of the machine frame in such manner that the cutting pull of the horizontal lever on the ram is downward and tends to draw the housing down upon the frame, thus insuring rigidity and accuracy of work for a long 35 period of time.

In the accompanying drawings Fig. 1 shows a vertical section of a vertical shaper attachment that embodies the invention. Fig. 2 shows a front view of the upper portion 40 of the machine frame with the housing and horizontal lever in operative position.

The top of the frame 1 of the common form of horizontal shaper has ways 2 covered by gib plates 3 in which the horizontal ram slides back and forth. In carrying out 45 this invention the housing 4 has fastened to its under side bars 5 that are shaped and located to fit in the ways and be secured for holding the housing in position by the gib plates. The ram saddle 6 is held in the front

end of the housing by a pivot pin 7 that extends transversely through the lower end of the saddle and the forwardly extending sides 8 of the housing. Clamp screws 9 project outwardly from the upper end of the saddle 55 through slots 10 in the sides of the housing for securing the upper end of the saddle. By this means the saddle may be positioned so that the tool will make an exact vertical cut or the saddle may be tilted so that the tool 60 will make an oblique cut on any desired angle approximately vertical. With the saddle pivoted at its lower end the desired angular path of the tool may be obtained without carrying the point of the tool a great distance forward over the work table.

The ram 11 is fitted to move up and down in a way in the front of the saddle. At the lower end of the ram is a box 12. This box is clamped to the bottom of the ram by a 70 binder stud 13 that is drawn upward by the wedges 14 and screw 15. Held in the box by pivot pin 16 is a block 17 which has a vertical opening for the cutting tool 18 of approved shape and a set screw 19 for fastening the tool in the opening. A spring 20 between the box and block tends to hold the point end of the tool forward. By loosening the screw 15 the box and block may be turned for setting the tool in the desired position 75 rotatorily of the ram.

In the ram is a connector block 21. The ram is adapted to be adjusted up or down with relation to this block for raising or lowering the tool by means of the feed screw 80 22 that is turned by the handle 23. When the relation of the ram and connector block are determined, the parts are fastened together by clamp screw 24. An ear on the connector block is held between the forked 85 end of the horizontal lever 25 by a pivot pin 26. The other end of this lever is forked and is free to slide on a spool 27 which is mounted on the pivot pin 28 that is supported by the side walls of the housing. A 90 plate 29 is fastened to this forked end of the lever and a cover plate 30 is arranged over a hand hole in the housing adjacent to this end of the lever.

An arm 31 is adjustably fastened to the 100

lever between its ends by a nut 32, the arm extending through a vertical slot 33 and the nut lying in a horizontal slot 34 in the lever. When the nut is loosened the arm may be 5 adjusted toward or from either end of the lever. This arm is joined by a connecting rod 35 with leg plates 36 that are fastened to or may be cast integral with the lower end of the crank lever 37 adjacent to the pivot 38 10 which supports the crank lever. The crank lever is oscillated by the crank block 39 that is pivotally attached to a gear 40 and is movable in a slot 41 in the lever. The crank gear is engaged and rotated by a driving 15 pinion 42 in the usual manner.

When the machine is arranged as a horizontal shaper the upper end of the crank lever is connected directly with the ram that is mounted in the ways at the top of the 20 frame as is well known to those familiar with this type of machine. To set up the machine as a vertical shaper, the housing is placed on the ways normally occupied by the horizontal ram and secured in position by 25 the gib plates, and the connecting rod is joined to the leg plates that are attached to or formed integral with the lower end of the crank lever adjacent to its pivot. To change back to the horizontal shaper the connecting 30 rod is disconnected from the leg plates and the gib plates unfastened, then the vertical attachment can be removed and the horizontal ram substituted. This attachment can, of course, be built as an integral part 35 of the machine where only a vertical shaper is wanted, but it is more especially designed for application to a horizontal shaper which has already been built and in common use, or where both types of shapers are desired 40 for a single frame and operating mechanism. The housing of this attachment may be adjusted on the top of the frame to any desired position to bring the tool to the required location with relation to the work, before the 45 housing is secured. With the mechanism described the pull of the connecting rod and horizontal lever during the down or cutting stroke of the ram is straight downward so that the tendency of the forces is to pull the 50 housing down upon the frame. There is no upward pressure on the housing when work is being done. This ensures rigidity which is essential to accuracy and relieves the housing fastenings of strain so that the desirable 55 condition will exist for a long time.

The invention claimed is:

1. The combination with a shaper frame having a crank actuated lever, of a housing secured to the top of the frame, a saddle mounted on the housing, a ram movable up and down on the saddle, a tool holder attached to the ram, a horizontal lever pivotally mounted in the housing, means joining the lever with the ram, a connecting rod

joined to the lever, and means projecting from the crank actuated lever, jointed to the connecting rod, whereby the oscillations of the crank lever through the connecting rod and horizontal lever reciprocate the ram substantially vertical. 65 70

2. A shaper attachment comprising a housing adapted to be secured to the top of a shaper frame which has a crank lever, a saddle mounted on the housing, a ram movable up and down on the saddle, a tool holder attached to the ram, a horizontal lever pivotally mounted in the housing, means joining the lever with the ram, a connecting rod jointed to the lever, and means jointed to the connecting rod and adapted to be secured to 80 the shaper crank lever. 85

3. A shaper attachment comprising a housing adapted to be secured to the top of a shaper frame which has a crank lever with an angular extension at its lower end, a saddle pivotally mounted on the housing, means for adjusting the saddle with relation to the housing, a ram movable up and down on the saddle, a tool holder attached to the ram, a horizontal lever pivotally mounted in the housing, means joining the lever with the ram, and a connecting rod jointed to the horizontal lever and to the angular extension of the shaper crank lever. 90

4. A shaper attachment comprising a 95 housing adapted to be secured to the top of a shaper frame which has a crank lever, a saddle pivoted at its lower end to the housing, means adjustably securing the upper end of the saddle to the housing, a ram movable up and down on the saddle, a tool holder attached to the ram, a horizontal lever pivotally mounted in the housing, means joining the lever with the ram, a connecting rod jointed to the lever, and means jointed to the connecting rod and adapted to be secured to the shaper crank lever. 100 105

5. A shaper attachment comprising a 110 housing adapted to be secured to the top of a shaper frame, a saddle pivotally mounted on the housing, a ram movable up and down on the saddle, a tool holder attached to the ram, a horizontal lever slidably mounted on a pivot carried by the housing, a jointed connection between the lever and the ram, 115 a connecting rod jointed to the lever, and means jointed to the connecting rod for moving it up and down.

6. A shaper attachment comprising a 120 housing adapted to be secured to the top of a shaper frame which has a crank lever, a saddle pivotally mounted on the housing, a ram movable up and down on the saddle, a tool holder attached to the ram, a horizontal lever pivotally mounted in the housing, a 125 connector block joining the lever with the ram, means for adjusting the relation of said block and the ram, a connecting rod

jointed to the lever, and means jointed to the connecting rod and adapted to be secured to the lower end of the shaper crank lever.

7. A shaper attachment comprising a housing adapted to be secured to the top of a shaper frame, a saddle mounted on the housing, a ram movable up and down on the saddle, a tool holder attached to the ram, a horizontal lever slidingly mounted on a pivot held in the housing, a connection block 10 between the lever and the ram, and means connected with the lever between the pivot and the connection block for pulling the lever down and thereby drawing the ram down.
